ELECTRONIC CONTROL PANEL

Myron R. Smith, Minneapolis, and Stanley W. Nickells, St. Louis Park, Minn., assignors to Minneapolis-Honeywell Regulator Company, Minneapolis, Minn., a corporation of Delaware

Application January 23, 1948, Serial No. 144,006

Term of patent 14 years

(Cl. D26—5)

To all whom it may concern:

Be it known that we, Myron R. Smith and Stanley W. Nickells, citizens of the United States, residing in Minneapolis and St. Louis Park, respectively, in the county of Hennepin and State of Minnesota, have invented a new, original, and ornamental Design for an Electronic Control Panel, of which the following is a specification, reference being made to the accompanying drawing, forming a part thereof, and in which:

Figure 1 is a front elevational view of an electronic control panel embodying our new design;

Figure 2 is a side elevational view of the same taken from the right side of Figure 1 looking left; and

Figure 3 is a perspective view of the same looking from the top and to the left.

We claim:

The ornamental design for an electronic control panel, substantially as shown.

MYRON R. SMITH.
STANLEY W. NICKELLS.
